UNITED STATES PATENT OFFICE.

JOHN PENROD, OF BEGGS, AND ROBERT D. THOMPSON, OF OKMULGEE, OKLAHOMA.

OIL WELL.

1,413,130.

Specification of Letters Patent. Patented Apr. 18, 1922.

Application filed November 10, 1920. Serial No. 423,082.

REISSUED

To all whom it may concern:

Be it known that we, JOHN PENROD and ROBERT D. THOMPSON, citizens of the United States, residing at Beggs and Okmulgee, in the county of Okmulgee, State of Oklahoma, have invented a new and useful Oil Well, of which the following is a specification.

This invention relates to oil well pumps, it being the object of the invention to provide a plunger of a novel construction designed to eliminate sand or gravel passing upwardly through the valves of the pump.

A further object of the invention is to provide a pump of this character including a sand pocket to receive the sand or gravel, and direct the same to the well.

A still further object of the invention is to provide a clutch mechanism for automatically clutching the pump rod to the sucker heads of the pump, the clutch being designed to automatically release the pump rod, when the pump rod has been moved to a predetermined position.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

Referring to the drawings:—

Figure 1 illustrates a vertical sectional view through the upper section of a working barrel, showing the pump rod and valve member clutched thereto.

Figure 2 illustrates a vertical sectional view through a portion of the working barrel and valve adjacent to the structure as shown by Figure 1.

Figure 3 illustrates a vertical sectional view through the lower section of the working barrel disclosing the lower pump valve.

Figure 4 illustrates a vertical sectional view through the extreme lower end of the working barrel.

Figure 5 illustrates a sectional view taken on line 5—5 of Figure 1.

Figure 6 illustrates a sectional view taken on line 6—6 of Figure 1.

Figure 7 illustrates a sectional view taken on line 7—7 of Figure 4.

Referring to the drawings in detail, the reference character 5 designates the tubular

plunger of the pump which is supported within the working barrel 44 which is positioned in the outer casing 6, the lower extremity of the casing having connection with the bushing 7 as by means of the threads 8, which bushing 7 also provides a support for the lower casing 8 which terminates in a bell bottom 9, which bell bottom provides the entrance to the casing 6 of the pump.

The bushing 7 also provides means of support for the tube 10 which is housed by the casing 8, the lower extremity of the tube 10 having connection with the intake pipe 11 which is provided with a plurality of openings 12 to admit fluid to the interior of the intake pipe 11, the intake pipe being positioned in the well. 75

Supported within the tube 10 is a spacing sleeve 13 which is threaded interiorally to accommodate the removable valve ring 14 which is provided with a valve seat 15 designed to accommodate the valve member 16 80 held in its operative position as by means of the valve spider 17, the valve member 16 being for the purpose of controlling the passage of fluid through the tube 18.

The tube 18 extends upwardly within 85 the tube 10, and is connected to the valve ring as by means of the securing sleeve 19, the upper end of the tube 18 being disposed within the bushing 7, at a point directly below the ball valve 20 to permit air and gas to 90 pass upwardly and through pipe 18 to pass off with the fluid on its passage through the pump. The ball valve 20 is supported by the bushing 7 and operates in the valve cage 21 to control the passage of fluid 95 within the working barrel 44.

The tube 10 is provided with inlet openings 22 adjacent the upper end thereof, whereby fluid may pass upwardly between the casing 8 and tube 10 and into the passageway formed between the vacuum tube 18 and the tube 10. 100

At the upper end of the plunger 5 is supported the clutch head indicated at 23, which has the clutch members 24 pivotally supported within the clutch head, the lower ends of the arms having connection with the clutch members 25, while the upper extremities thereof are normally forced outwardly by means of the coiled springs 26, the upper 110 ends of the arms being however curved as at 27 to cooperate with the inclined wall 28 of the head 29. From the foregoing it is obvious that as the clutch head is moved up-

wardly to cause the arms 24 to contact with the inclined wall 28, the upper ends of the arms are cammed inwardly causing the lower ends of the arms to move the clutch members 25 out of the circumferential groove 30 formed in the valve rod 31.

The valve rod is connected to the pump rod 32 as by means of the head 33 which is internally threaded to receive the threaded 10 stem 34 of the valve stem, the lower portion of the valve stem being separable and connected to the upper portion as by means of the threaded extension 35, the lower portion of the valve stem being however formed into 15 a valve cage 36 to accommodate the ball valve 37, which seats on the valve seat 38 and controls the passage of fluid into the upper portion of the casing.

The lower valve stem 39 has connection 20 with the lower valve cage 42 in which operates the valve 41, the cage carrying valve barrel 40' on the lower end thereof, which valve barrel is hollow and supports packing rings 41' on the periphery thereof to insure 25 a fluid-tight connection between the valve barrel and the bushing 42', the bushing being shown as threaded and having a circumferential flange 43' to connect the same to the plunger 5. The valve barrel 24' is 30 provided with a plurality of openings 43 to permit the passage of fluid into the plunger.

The plunger 5 also moves in the working barrel 44, there being provided suitable packing 45 carried at the upper end of the barrel 44 for insuring a fluid tight connection between the plunger 5 and the working barrel 44.

In the operation of the device, the rod 32 40 is reciprocated by any suitable means, whereupon fluid is sucked through the bell bottom of the casing 8, where the same passes upwardly, and is drawn through the openings 22 and into the casing between the tube 10 and tube 18, where the same passes upwardly 45 over the upper end of tube 18 past the ball valve 20 and into the working barrel 44. It is obvious that as the fluid passes to the upper end of the tube 10, the sand or gravel 50 drops through the sand pocket or space formed between the tube 10 and tube 18, thereby eliminating any possibility of the valve members contacting with the sand to render the same inoperative.

If it is desired to remove the valves from the plunger 5 it is only necessary to move the rod 32 upwardly until the upper curved 55 extremities of the arms 24 contact with the inner curved wall of the head 29, whereupon the clutch members 25 release their hold on the valve rod 31 to release the same, the plunger 5 together with the clutch members drops to a position to rest at the upper end of barrel 44. It follows that by further movement of the rod 32, the valve rod 31 together

with the valve members may be removed for purposes of repair.

From the foregoing it will be seen that owing to the fact that the plunger 5 is of a greater diameter than the well tubing supported thereabove, a greater displacement is insured to the end that a greater volume of fluid is forced through the tubing, at the same time the structure is such as to permit the valves to be removed for repair.

Having thus described the invention, what is claimed as new is:—

1. In a device of the character described, a casing, a working barrel within the casing, a plunger within the working barrel, a pump 80 rod extending into the plunger and carrying valves, means for clutching the plunger to the pump rod, and means for automatically disengaging the clutching means.

2. In a device of the character described, 85 a casing, a working barrel within the casing, pivoted arms carried at the upper end of the plunger, a pump rod adapted to move into the plunger, said pump rod having a circumferential groove, means carried by the arms 90 and adapted to move into the groove for clutching the plunger to the pump rod, means for automatically disconnecting the plunger and pump rod, and valve members carried by the pump rod.

3. In a device of the character described, a casing having a head, said head having an inclined wall, a plunger within the casing, a pump rod extending into the plunger, means for clutching the pump rod to the plunger, 100 said means including pivoted arms having inclined surfaces adapted to contact with the inclined surface of the head for unclutching the pump rod and plunger, and valve members carried by the pump rod.

4. In a device of the character described, a casing, a plunger supported within the casing, a pump rod extending into the casing, said casing having a head, means for clutching the pump rod to the plunger, and 110 said clutching means adapted to be moved out of operation by contact with the head.

5. In a device of the character described, a casing, a plunger movable within the casing, a pump rod extending into the plunger 115 and carrying valves, arms pivotally carried by the plunger, means supported at the ends of the arms and adapted to contact with the pump rod for clutching the plunger to the pump rod, and spring members for normally 120 holding the arms in clutching positions.

In testimony that we claim the foregoing as our own, we have hereto affixed our signatures in the presence of two witnesses.

JOHN PENROD.
ROBERT D. THOMPSON.
